UNITED STATES PATENT OFFICE.

ARTHUR A. ARNOLD, OF HARTFORD, CONNECTICUT, ASSIGNOR TO AMERICAN OPTICAL COMPANY, OF SOUTHBRIDGE, MASSACHUSETTS, A VOLUNTARY ASSOCIATION OF MASSACHUSETTS.

GRINDING MACHINE.

Application filed July 8, 1919. Serial No. 309,344.

To all whom it may concern:

Be it known that I, ARTHUR A. ARNOLD, a citizen of the United States, residing at Hartford, in the county of Hartford and 5 State of Connecticut, have invented certain new and useful Improvements in Grinding Machines, of which the following is a specification.

This invention relates to improvements 10 in lens grinding machinery and has for its leading object the provision of a novel and improved construction of such machinery in which the driven spindle may be operated at different rates of speed as desired.

15 A further object of the present invention is the provision of mechanism of this character which shall be simple of operation and readily mounted and contained within the base of the machine in a simple and satisfactory manner.

20 A further object of the invention is the provision of a lens grinding machine which shall be automatic in operation, and in which the speed of such automatic operation may be varied as desired.

25 A further object of the invention is the provision of a novel and efficient machine particularly adapted for the automatic production of toric or cylindrical lenses.

30 Other objects and advantages of my improved construction should be readily apparent by reference to the following specification taken in connection with the accompanying drawings, and it will be understood that I may make any modifications in 35 the specific details of construction shown and described within the scope of the appended claim without departing from or exceeding the spirit of my invention.

40 Figure I represents a view partially in perspective and partially in section, of my improved simplified lens grinding machine.

Figure II represents a fragmentary view 45 of the switch and control mechanism.

45 Figure III represents a plan view showing the throw adjustment disc.

50 In the drawings, the numeral 1 designates the base of my improved lens grinding machine which is similar in general appearance to the ordinary electric surface grinder of the present day, having the space 2 adapted to receive an actuating motor, which in ordinary practice is directly connected with the shaft 3 adapted to receive a lens or

lens holder on its tapered upper end 4. I 55 have here shown the member 4 as forming a portion of a cap or toric attachment fitted on the spindle 3 and provided with the arms 5 for engagement with the arms of a regular toric or cylinder lens grinding block such as 60 is well known in the art. In my improved construction, however, in place of having the motor directly secured or connected to the shaft 3, I make use of my improved driving connections. The base 1 is shown as provided 65 with the spider type frame 6, providing the journal 7 containing the bushing 8, in which the shaft 3 rotates, and on the lower end of which is rotatably mounted the gear 9. This 70 gear 9 is loosely mounted upon the bushing 70 and has a different number of teeth from the adjacent gear 10, the gears 9 and 10 being in mesh with the pinions 11 carried by the pinion plate 12, which is loosely or rotatably mounted on the lower end of the shaft 3, the 75 gear 10 being keyed on the shaft between the pinion plate and the gear 9.

Slidably keyed on the upper end of the motor shaft 13 is the clutch spool 14 provided on its upper face with the clutch portion 15 80 adapted when in open position to interlock with the clutch member 35 on the shaft 3 and being further provided with the drive pin 17 adapted to engage in the pin groove 18 and abut the end of the groove whereby 85 the pin serves to impart rotary motion to the pinion plate 12. To shift the various parts as desired, I make use of the bell crank 19 pivoted as at 20 to the base 1, and having its end engaged by the collars 21 on the L 90 shaped shift rod 22 provided with the operating handle 23.

This shift rod may be slid in and out through the yoke 24 of the bell crank, to slide the spool 14 up and down or toward 95 and away from the shaft 3.

It will further be noted that the frame 1 is provided with a suitable guide bracket having the notches 25, 26 and 27 disposed at different distances from the frame. When 100 the handle 23 is swung to bring the rod 22 into the notch 27 the clutch will be depressed and entirely out of engagement with the lens grinding parts, so that the motor may rotate freely. When the handle is shifted to engage the shift rod 22 in the notch 26 the bell crank will be partially rocked to cause the pin 17 to interlock with the pinion plate 105

12 to drive the pinion plate. At the same time the inner end of the rod 22 will contact with the abutment pin or lug 28 on the gear 9 and hold this gear against rotation. The effect then will be that the member 12 rotates carrying with it the pinions 11, while as the gear 9 is held against rotation the pinions will roll around on the gear and thus impart a slow relative movement to the gear 10, and through the gear 10 to the shaft 3, slowly rotating this shaft and any parts which may be carried by it. When it is desired to operate the shaft at a higher rate of speed the lever is again shifted into the notch 25, when the pin 17 will still be in engagement with and drive the pinion plate 12 and at the same time the clutch face 15 will interlock with the member 35 on the drive shaft 3 to give a direct drive between the two shafts. This further shifting of the lever 22, it will be understood, is sufficient to withdraw its end from engagement with the pin 28 so that the pinions 9 will be bodily carried around by the synchronously rotating gear 10 and pinion plate 12.

It is to be noted that I have shown in connection with this form of mechanism as clamped to the edge of the frame or support 1 that carries the pan 29, the sleeve 30 within which is rotatably mounted the stud shaft 31 bearing at one end of the pulley 32 and at the other the eccentric disc 33. The pulley 32 is connected by the belt 34 with the belt groove 16 on the pinion plate 12 so that the shaft 31 will rotate with the pinion plate when driven. Mounted in the slot 36 of the eccentric disc 33 secured on the other end of the shaft is a suitable T-head bolt 37 having mounted on it the clamping sleeve 38 by which the bolt may be tightened in transversely adjusted position in the slot to vary its eccentric relation to the stud shaft 31, while rotatably mounted on the sleeve 38 is the block 39 to which is pivoted the lever arm 40 bearing the lens holder engaging pin 41 and projecting across the pan between the guide arms 42, having on its other end the spring 43 for holding it down in operative position, a hook 44 on the holder 45 of the guide arms cooperating with the chain 46 on the end of the spring to facilitate adjustment of the spring tension. Both the member 45 and the sleeve 30 are detachably clamped to the member 1 and

may be employed or not as desired, but when employed in connection with a machine of this character are extremely desirable in that they relieve the operator of the necessity of holding a lever by hand and working it transversely of the lap during the grinding and perform these functions automatically, the motion imparted through the use of the eccentric being a substantially circular sliding movement of the pin 41, which in connection with the rotation of the shaft or spindle 3 will produce a very satisfactory lens grinding effect.

It is to be understood, however, that my driving mechanism is equally applicable and employable with the belt 34 and all other parts removed and in their absence will give me a satisfactory two speed grinding machine, giving me a slow speed for work requiring less speed, and more power and a high speed as for polishing or the like where relative lap movement of the surface is desired, and that I have provided a novel and improved form of electrically or other driven surfacing machine capable of ready variations of the speeds by movement of the shift lever 23 or of stopping the machine without stopping the source of power without disconnecting the driven spindle 3 from the source of power.

I claim:

In mechanism of the character described, the combination with a driven shaft and a driving shaft, of clutch members carried by said parts for direct drive engagement, and means for operating the driven shaft at a reduced rate of speed, including a spider member having a pulley portion, pinions rotatably mounted on the spider member, a pair of gears having unequal numbers of teeth, one of said gears being fixed on the driven shaft and the other being loosely mounted, and progressive operating clutch mechanism for driving the spider from the driving shaft when in one adjustment and for driving both the spider and the driven shaft when in a second adjustment, substantially as illustrated.

In testimony whereof I have affixed my signature, in presence of two witnesses.

ARTHUR A. ARNOLD.
